UNITED STATES PATENT OFFICE.

GEORGE P. FENNER, OF NEW LONDON, CONNECTICUT.

PISTON.

SPECIFICATION forming part of Letters Patent No. 268,654, dated December 5, 1882.

Application filed August 21, 1882. (No model.)

To all whom it may concern:

Be it known that I, GEORGE P. FENNER, a citizen of the United States, residing at New London, in the county of New London and State 5 of Connecticut, have invented new and useful Improvements in Pistons, of which the following is a specification.

This invention relates to an improvement in pistons for air or liquid pumps and other purposes; and it consists in the means hereinafter described for adjusting a piston to its cylinder.

This invention is illustrated in the accompanying drawings, in which Figure 1 represents a central cross-section. Fig. 2 is a side view. Fig. 3 is a like view, partly in section.

Similar letters indicate corresponding parts.

The letter A designates the head of a piston, cast or otherwise provided with a hub, B, 20 which is threaded externally, and on which is fitted an internally-threaded ring, C, provision being made for attaching the whole to a piston-rod—as by a threaded hole, D, going through the head and its hub. The hub B projects 25 from one side of the piston-head, where the latter carries also a ring, E, at or near the edge, such ring being attached or held in place by screws F or other suitable means; and between this ring and the head is interposed and 30 clamped a flange concomitant to a leather or other suitable packing ring, H. This packing-ring is of cylindrical form and rests upon the outer edges of a series of segments, I, which surround the hub B and are secured to the 35 ring E by means of screws J, passing through radial slots K in the segments, so that the latter are adjustable respectively in a radial direction.

On the inner edge of each segment I is a

flange, O, which projects in the direction of 40 and near to the piston-head, while between these flanges and the ring E are interposed springs N, of spiral form—one to each segment—which act on the segments with a tendency to retract or draw them inward.

Projecting in an opposite direction to the flange O, on the inner edge of the segments, is a tapering offset, P, and the screw-ring C is tapered in a suitable manner to engage such offset, so that when this ring is screwed in- 45 toward the segments it acts on the latter to force them outward, while when the ring is screwed in an outward direction it releases the segments and allows them to follow the action of their retracting-springs. Thus, by simply 50 moving the screw-ring C in the proper direction, the segments, together with the packing-ring, can be adjusted to the size of the cylinder in which the piston is used, so that, for example, any wear of either the cylinder or 55 piston can be readily compensated for.

What I claim as new, and desire to secure by Letters Patent, is—

The combination, substantially as hereinbefore described, with the piston-head A and its 60 externally-threaded hub B, of the tapering screw-ring C, the attached ring E, the flanged packing-ring H, the radially-adjustable segments I, each having a flange, O, and tapering offset P, and the segment-retracting springs N. 65

In testimony whereof I have hereunto set my hand and seal in the presence of two subscribing witnesses.

GEORGE P. FENNER. [L. S.]
